(57) **CLAIM**

The ornamental design for a computer screen, as shown and described.

DESCRIPTION

FIG. 1 is a left-front perspective view of a computer screen showing our new design.

FIG. 2 is a front view of the computer screen of FIG. 1.
FIG. 3 is a back view of the computer screen of FIG. 1.
FIG. 4 is a left side view of the computer screen of FIG. 1.
FIG. 5 is a right side view of the computer screen of FIG. 1.
FIG. 6 is a top view of the computer screen of FIG. 1; and,
FIG. 7 is a bottom view of the computer screen of FIG. 1.
The dashed broken lines in the figures depict portions of the computer screen that form no part of the claimed design.

1 Claim, 7 Drawing Sheets
